Primary Examiner — Rosemary K Tarcza*Assistant Examiner* — Nathaniel D. Buckner(74) *Attorney, Agent, or Firm* — Cheng-Ju Chiang(57) **CLAIM**

The ornamental design for a charger box of bluetooth headset, as shown and described.

DESCRIPTION

FIG. 1 is a top right perspective view of a charger box for a bluetooth headset showing my new design;
FIG. 2 is a bottom left perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof; and,
FIG. 9 is a top right perspective view thereof, shown in a position of use.

The broken lines in the drawings illustrate portions of the charger box of bluetooth headset which form no part of the claimed design.
